UNITED STATES PATENT OFFICE

95,894

DESIGN FOR AN ELECTRIC LOCOMOTIVE

Conrad C. C. Burkhardt, Philadelphia, Pa.

Application June 2, 1934, Serial No. 52,020

Term of patent 14 years

To all whom it may concern:

Be it known that I, Conrad C. C. Burkhardt, a citizen of the United States, residing in Philadelphia, Pennsylvania, have invented a new, original, and ornamental Design for an Electric Locomotive, of which the following is a specification, reference being had to the accompanying drawing, forming part thereof, in which:

Figure 1 is a plan view of the new electric locomotive, and

Fig. 2 is a side view.

The characteristic feature of the design is the

locomotive which has a lateral projection at each side at the forward end thereof, which projections have window openings at the side and at the rear portions thereof, and the locomotive having a door at one side and window openings on each side, all as clearly shown in Figure 2 of the accompanying drawing.

I claim:

The ornamental design for an electric locomotive, substantially as shown and described.

CONRAD C. C. BURKHARDT.
